UNITED STATES PATENT OFFICE.

CHARLES L. TRAVIS, OF MINNEAPOLIS, MINNESOTA.

INSULATOR.

SPECIFICATION forming part of Letters Patent No. 336,828, dated February 23, 1886.

Application filed November 14, 1885. Serial No. 182,804. (No model.)

To all whom it may concern:

Be it known that I, CHARLES L. TRAVIS, of Minneapolis, county of Hennepin, and State of Minnesota, have invented a new and useful 5 Improvement in Insulators, of which the following is a full, clear, and exact description, reference being had to the accompanying drawings, making part of this specification.

My invention relates to an improvement in 10 means for insulating electric lamps or wires from their supporting and adjusting devices; and it consists in the employment of an insulated hook or link adapted to be interposed between the supporting cord, wire, or device 15 and the lamp, as hereinafter fully set forth.

In the accompanying drawings, Figure 1 represents a perspective view of an electric lamp with my improvement applied, showing also the supporting and adjusting devices; and 20 Figs. 2 and 3 are transverse sectional views illustrating my insulator-hook.

A represents the supporting rod or wire by means of which the lamp is suspended or upheld in the desired position. This supporting-wire extends between two uprights or poles of any usual or preferred construction, and a traveling pulley-block, B, is mounted thereon. Said block B is of ordinary form, being composed of two cheek-plates having two grooved 25 revolving pulleys interposed—an upper one, b, which is adapted to travel upon the supporting-wire, and a lower one, b', over which the cord that supports the lamp passes.

C represents the lamp-support, which may 30 be a cord composed either of hemp or flexible wire, as preferred. Said supporting rope or wire is secured at one end to one of the uprights or posts between which the wire or support A is stretched, and, passing through the 35 pulley-block B, over the lower pulley, b', has the lamp secured to it, as hereinafter explained.

D represents the adjusting-cord or flexible wire rope, secured at one end to the pulley-block B by means of a yoke, d, spanning said block, or in any other suitable manner. From this point of attachment said adjusting-cord D extends to the upright or pole opposite that to which cord C is attached, and, passing over 40 a pulley thereon, extends downward to and is adapted to be wound upon a reel or windlass,

as described and illustrated in Letters Patent No. 329,510, granted to me November 3, 1885.

All the means above described for supporting and adjusting the lamp are fully set forth in my patent referred to, and operate in the same manner. Therefore it will not be necessary to describe said devices any further herein.

E represents the connecting hook, interposed between the end of the lamp-supporting cord and the lamp. It is made in substantially the form shown in Figs. 2 and 3—*i. e.*, with loops e e' at either end. Molded about and around one of these loops, preferably the upper and larger one, is a glass body, F, of 65 the form shown or any other suitable or preferred form, the object being to insulate the lamp-supporting cord from the lamp itself and the current passing through the hook E and its loop e.

Another and most important object of my invention is the provision for the safety of the lamp in the event of the breakage of the glass or insulating material surrounding the loop portion of the hook. The supporting-cord C, 70 passing through the perforation f of the insulating body or material, at the same time passes through the loop e of the wire hook E, and should the glass or insulating material F be shattered and fall from said hook E the cord 75 or wire C will still encircle and support the loop e, and thereby the hook E and its pendant lamp. The lamp is attached to the insulated hook E by means of the lower loop, e', 80 which passes through a staple or hook secured 85 to the upper portion of the lamp.

I have said above that I employed glass to insulate the hook E from the cord or wire C, and that the glass was molded around the same and the loop e; but it will be obvious that any 90 known or equivalent material for insulating purposes will accomplish the result I desire to obtain, and that whether molded or wrapped or otherwise placed thereon. Therefore I do not wish to be limited to the one material or 95 to the precise form of insulator-hook shown.

Having now described my invention, I claim as new—

1. The hook E e', having one of its loops, e, insulated by surrounding the same with an 100 insulating material in such manner as to form or leave a hole or perforation, f, for the at-

tachment of the supporting wire or cord, substantially as described.

2. The hook $E e e'$ and the supporting wire or cord passing through the loop or eye e thereof, 5 but insulated therefrom by means of glass or other insulating substance, molded or formed around and inclosing said loop or eye e , substantially as described.

3. The supporting and adjusting devices described, in combination with the hook $E e e'$, interposed between the lamp and its support.

ing-cord, said loop being provided with the insulating-body F , having the perforation or hole f , all substantially as and for the purpose described.

In testimony whereof I have hereunto set my hand.

CHARLES L. TRAVIS.
